DRYING DEVICE FOR TRAVELING WEBS

Theodor Fuykers, Dusseldorf, Germany

Application May 23, 1934, Serial No. 727,197
In Germany May 24, 1933

10 Claims. (Cl 34—48)

The invention relates to a device for drying traveling webs of all kinds, during their manufacture or treatment, for example printed paper or webs of other material, by means of a medium in the form of gas or vapour, for example air. The object of the invention is to provide as compact a construction as possible for such drying devices which, with the minimum requirements of space, render possible a particularly advantageous utilization of the drying effect of the drying medium. For this purpose, according to the invention, a web guide is provided which guides the traveling web for a certain length thereof in one direction, deflects it and returns it in at least substantially the opposite direction, and at two external sides of which are mounted the drying devices acting over the two lengths of web guide. The web guide comprises or is constituted by a series of parallel, adjacently disposed guide spindles. The web is then first led along one side of the series of spindles, is deflected round the last spindle and is returned along the other side of the series of spindles. The new arrangement according to the invention thus renders it possible to utilize a web guide, such as has been necessary heretofore for any drying device, on both sides for association with two drying devices, so that the individual drying devices do not require a separate rear wall and 30 separate guiding spindles.

The new arrangement requires much less space and material as compared with apparatus using large drying cylinders, and is therefore much more economical and convenient.

35 The web guide (roller band, guide spindles or the like) may be set into motion either by the traveling web itself or it may be driven separately. If individual guide spindles are employed, a sprocket wheel may be mounted for example on each spindle shaft, and the said sprocket wheels may be driven by a common chain drive.

In order, when the web guide is constituted by 45 guide spindles, to prevent sagging of the traveling web between the said spindles, the gaps between the spindles may be bridged by guide walls, above the surface of which the spindles project but slightly. The said guide walls may be adjustably mounted, so that their distance from the upper edge of the guide spindles may be varied. If the 50 axes of the guide spindles all lie in one plane and if the spindles all have the same diameter, two plane web guide lengths are obtained. If it is desired to guide the web in an arcuate manner, this may be readily accomplished, even in the 55 case of the arrangement of the spindle-axes in

one plane, by constructing the spindles of different diameters, for example, the middle guide spindle having the largest diameter, and the diameter of the spindles progressively diminishing towards each end of the series of spindles. 5

The form of the drying devices disposed on either side of the web guide may be as desired. It is possible to employ for example drying devices according to the co-pending application, Serial No. 523,578, filed on the 18th March, 1931, 10 now Patent No. 2,022,593 in which a plurality of blowing and suction nozzles are arranged alternately transversely to the direction of travel of the web. It has been found to be particularly advantageous to dispose parallel to each of the 15 two web guide lengths a conducting wall for the drying medium, for example air, to be passed between the said wall and the traveling web. The said guide walls may be adjustably mounted so that their distance from the adjacent surface 20 of the traveling web may be varied in order to secure the best drying effect. It is advisable to make the distance of the guide walls from the traveling web above each guide spindle less than that between the guide spindles. The flowing 25 drying medium is thereby baffled at these places, and hence an increase in pressure is obtained, which is particularly advantageous in preventing contact of the traveling web with the guide walls. The diminution in distance at the said points 30 may be obtained by providing the guide walls with a transverse rib, elevation or the like directed towards the corresponding spindle. 35

The drying medium flowing through the space 40 between the guide walls and the traveling web 35 may be injected at one end of the guide walls into the said space and may be led off freely or aspirated at the other end. It is also possible to force the drying medium through the drying length merely under the influence of suction. It 45 has been found to be a particularly advantageous arrangement to provide, opposite the deflecting point of the traveling web, a drying air supply container, from which the air flows into the drying devices situated on either side of the web 50 guide. The said container may be of any desired construction. If guide walls parallel to the web are employed, the drying medium flowing from the said container and passing between the web and the guide walls may be led off, for example by aspiration at the ends of the guide lengths, that 55 is to say, at the points at which the web enters and leaves the drying device. A particularly compact arrangement is provided when the drying air is deflected at these points to the rear side 55

of the guide walls and is led along the latter into a suction air collecting container, which may be constructed conjointly with the drying air supply container. It has been found to be advantageous 5 to form the drying air supply container of a longitudinally slotted, preferably conical tubular member closed on one side, the two guide walls adjoining the edges of the slit in the said tubular member, so that the drying medium flows out of 10 the longitudinal slit between the two guide walls, and to construct the suction air collecting container in the form of a concentric tubular member, the edge of which has a longitudinal aperture of a sufficient size to allow of the passage 15 of the guide walls and of the admission of the suction air, the external walls of the suction air channels being connected to the edges of the said aperture.

Advantageously, it is also possible to bring the 20 end edges of the guide walls close to the surface of the travelling web, and then to bend them over rearwardly in the direction of the suction air current. Since the deflecting points of the drying medium are situated in the vicinity of the inlet 25 and outlet of the web in the drying apparatus, special measures are preferably taken to prevent the escape of drying medium through the inlet and outlet slits. For this purpose, the walls which effect the deflection of the drying medium 30 may be extended so far towards the central plane of the drying device that the inlet and outlet slit of the web does not lie in the direction of flow of the current of drying medium. Furthermore, special baffle surfaces for the drying air to be 35 deflected may be provided at the ends of the guide lengths. Preferably, these surfaces also may be extended towards the centre of the drying device so far that the deflected current of drying air does not strike their end edges. The passage 40 of drying air through the gaps between the baffle surfaces and the traveling web cannot of course be prevented completely. A portion of the drying medium will therefore be deflected already by the baffle surfaces, while a further portion, 45 only deflected by the external walls, will flow on the rear of the baffle surfaces and into the suction channel. This phenomenon, however, may be utilized for regulating the suction, the baffle surfaces being extended in the direction of the suction 50 air current and carrying adjusting means, so that thereby the cross-sections of flow may be adjusted. It is thus possible to arrange for the main portion of the suction to be effective on the front or on the rear of the baffle surfaces. Of 55 course, a plurality of the latter may be provided.

Another form of construction of the drying device is obtained if the two guide walls at the deflecting point of the web are allowed to merge 60 into one another, and the drying medium is introduced at the inlet or outlet of the web and is led away at the outlet or inlet. The more preferable construction will be to allow the drying medium to flow in a direction contrary to that of the web travel. Finally, it is possible to introduce the drying medium both at the inlet and at the outlet of the web, to deflect both drying medium currents outwardly at the deflecting point of the web, to return them back to the points of introduction and from thence to lead them 65 away.

All of the constructional forms of the present device are preferably such that the parts covering the web can be removed or at least hingedly opened on one side for convenience in drawing 70 in the web and for inspection purposes.

Forms of construction of the invention are shown by way of example in the drawing, in which:—

Figure 1 is a side-view of a printing machine with two drying devices connected to a common 5 blowing and suction container;

Figure 2 a partial longitudinal section along line E—F of Figure 1;

Figure 3 a transverse section along line A—B of 10 Figure 1;

Figure 4 a section along line C—D of Figure 1;

Figure 5 a detail view, partly in section, showing one of the baffle surfaces arranged near the inlet end of the machine.

In the first form of construction, the web guide 15 consists of ten spindles 1 to 10, the shafts of which lie parallel and adjacent to one another in one plane, and are journaled in two stationary side walls 11 and 12 of the drying device. The shafts are extended outwardly on one side to project beyond the wall 12 and carry sprocket wheels 13, which are driven by a chain 14 as indicated in 20 Figure 2. The middle spindles 5 and 6 have the largest diameter, and the diameter of the spindles diminishes progressively towards each end of the 25 drying lengths. Mounted between the guide spindles are guide walls 15 and 16 as shown in Figures 1, 3 and 4, secured by angle pieces 17 and 18 (Figure 3) to the side walls 11 and 12. The attachment by means of screws enables the vertical position of the guide walls with respect to the upper edges of the corresponding guide spindle to be selected according to requirements. The traveling web 19 first passes onto the spindle 1, and thence over all the spindles as far as 30 spindle 10, is deflected round the latter and passes back again along the other side of the guide spindles to the spindle 1, whereupon it can be given any desired direction by means of the guide roller 20. The direction in which the web runs 40 onto and off the spindles is so selected that the initial and final points of contact of the web with the guide spindle 1 are not disposed diametrically, but nearer to the central plane of the 45 drying device.

Opposite the last guide spindle 10 is mounted 50 the joint drying air supply and suction air collecting container. It comprises the conical tubular member 21, into which the drying air enters in the direction of the arrows 22. On the side facing the spindle 10 the tubular member has a longitudinal slit 23, from which the drying air flows in the direction of the arrows 24 towards the spindle 10 and, from the latter, away on either side of the web guide in two streams along the 55 traveling web. At the same time, the air is maintained in contact with the surface of the web by two guide walls 25 and 26, which adjoin the edges of the slit 23. The two guide walls are respectively provided above each guide spindle with a transversely-extending elevation 27, 28. At the bottom ends, they are likewise first bent towards the paper web and then back into the suction direction, as shown at 29 and 30. Extending parallel to the guide walls 25 and 26 are the two 60 external walls 31 and 32 of the device, which constitute with the guide walls the suction channels in which the drying medium, deflected round the ends 28 and 30 of the guide walls, returns to the starting point. The external walls are connected to the semi-circular tubular member 33, which forms the suction air collecting container and from which the air is aspirated in the direction of the arrows 34. The external walls 31 and 32 are bent inwardly at one of their ends, namely, 70 75

35 and 36 respectively, which ends extend close to the surface of the traveling web at its points of contact with the guide spindle 1. The drying medium flowing against the wall-ends 35, 36 is deflected by them into the suction direction. This deflection is also effected by the two baffle surfaces 37 and 38 which are also provided. Figure 5 shows how both the end of the external wall 36 and that of the corresponding baffle surface 38 may be shifted from the highest point of the guide spindle 1 towards the central plane of the web guide such a distance that the drying air current flowing in the direction of the arrow 39 does not reach the gap between the baffle 15 and the web. Nevertheless, of course, all the air will not be deflected in the direction of the arrow 40 by the baffle surface 38, but a portion will flow under the edge thereof and back in the direction of the arrow 41. The angle members 42, 20 43, 44, 45 (Figure 3) serve as supports for the guide walls 25 and 26, the external walls 31 and 32 and the baffle surfaces 37 and 38. The said members lie loosely on the walls 11 and 12, with the interposition of packings. The lower portions 25 35 and 36 of the outer walls 31 and 32 are fixed and form the bearings for the hinges 46 and 47, about which the parts of the drying devices described can be swung open. At the ends 48 and 49, the guide walls 25 and 26 are applied 30 with packings against the drying air supply pipe 21. The collecting pipe 33 is hinged as at 50 to the external wall 32 and may be swung thereabout, while the pipe 21 is fixed. The guide walls 25 and 26 are secured to lateral angle members 35 51 and 52, which can be screwed fast to the angle members 42 to 45 by means of screws 53, 54. The screws 55, 56 which pass through the external walls 31 and 32 at the edges of the device serve for fine adjustment. The ends 37' and 38' 40 of the two baffle surfaces 37 and 38, which are extended rearwardly in the suction direction, may likewise be adjusted by means of screws 57 (Figures 1 and 4). It is thereby possible to vary the width of the passage between the ends 29 and 30 45 of the guide walls and the baffle surfaces, and also between the external walls and the baffle surfaces and thus to regulate the suction.

I claim:

1. A device for drying by means of a gaseous medium traveling webs printed on one side thereof, said device comprising a casing, guide-walls in said casing, said walls forming a narrow channel along the printed side of said web, a web-guide for feeding said web through said channel, means for blowing said gaseous drying medium into said channel at one end thereof along said printed side of said web, and suction means for withdrawing said medium at the other end of said channel.
2. A device for drying by means of a gaseous medium traveling webs printed on one side thereof, said device comprising a casing, guide-walls in said casing, said walls forming a narrow channel along the printed side of said web, a web-guide for feeding said web from one end of said casing through said channel along said guide-walls round a reversing point and back to said one end of said casing, means for blowing said gaseous medium into said channel at one end thereof along said web when being fed therethrough by said web-guide, and suction means provided at the other end of said channel for withdrawing said medium from said printed side of said web.
3. A device for drying by means of a gaseous

medium traveling webs printed on one side thereof, said device comprising a casing, guide-walls in said casing, said guide-walls forming a relatively long and narrow channel embracing said web, guide-means for feeding said web into and out of said casing through said channel, a container arranged midway with respect to said channel for supplying said medium to the printed side of said web when passing said container, and suction means for withdrawing said medium at the ends of said channel.

4. A device for drying by means of a gaseous medium traveling webs printed on one side thereof, said device comprising a casing, guide-walls in said casing, said walls forming a channel passing from one end of said casing round a reversing point back to the other end of said casing and closely embracing the web, a web-guide for feeding said web through said channel from the one to the other end thereof, a container arranged midway with respect to said channel for supplying said medium under pressure to the printed side of said web when being fed through said channel by said web-guide, and suction means provided at one end of said casing and near both ends of said channel for withdrawing said medium from the latter.

5. A device for drying by means of a gaseous medium traveling webs printed on one side thereof, said device comprising a casing, guide-walls in said casing, said walls forming a channel passing from one end of said casing round a reversing point back to the other end of said casing and closely embracing said web, a web-guide for feeding said web through said channel from the one to the other end thereof, means for supplying said medium to the printed side of said web at the reversing point of said channel, and suction means arranged at the ends of said channel for withdrawing said medium after passage through said channel.

6. A device for drying by means of a gaseous medium traveling webs printed on one side thereof, said device comprising a web-guide adapted to feed a web in forward and backward direction through said device, guide-walls forming a narrow channel closely embracing said web when being fed through said device, means for supplying said gaseous medium to said channel at one end thereof to move alongside the printed side of said web, and suction means at the other end of said channel for withdrawing said gaseous medium therefrom.

7. A device for drying by means of a gaseous medium traveling webs printed on one side thereof, said device comprising a casing, guide-walls in said casing, said walls forming a relatively narrow channel adapted for the reception of the web, a web-guide for carrying said web through said channel, pressure-means for supplying said medium to said channel at one end thereof, suction means for withdrawing said medium at the other end of said channel, and means for varying the cross-section of the latter.

8. A device for drying by means of a gaseous medium traveling webs printed on one side thereof, said device comprising a casing, guide-walls in said casing, said walls forming a narrow channel closely embracing said web and passing through said casing from one end round a reversing point back to the other end, a web-guide for feeding said web through said channel from the one to the other end thereof, a container arranged midway with respect to said channel for supplying said medium under pres-

sure to the printed side of said web when being fed through said channel by said web-guide, suction means provided at one end of said casing and near both ends of said channel for discharging said medium from the latter, and means for varying the cross-section of said channel.

9. A device for drying by means of a gaseous medium travelling webs printed on one side thereof, said device comprising a casing, guide-walls 5 in said casing, said walls forming a relatively long and narrow channel extending in forward and backward direction round a reversing point, an inlet at the one and an outlet at the other end of said channel, a series of rollers disposed 10 one behind the other and arranged within said casing to guide said web through said channel from said inlet past said reversing point back towards said outlet, a container near said reversing point for supplying said gaseous medium 15 to the printed side of both web runs on said rollers, and suction means for withdrawing said

medium from the ends of said channel after passage along the printed side of said web.

10. A device for drying by means of a gaseous medium traveling webs printed on one side thereof, said device comprising a casing, guide-walls 5 in said casing, said walls forming a relatively long and narrow channel extending in forward and backward direction round a reversing point and enclosing the traveling web, an inlet and an outlet for the web on said channel, a series 10 of rollers disposed one behind the other and arranged within said casing to guide said web through the whole of said channel from said inlet over said rollers to said reversing point and back to said outlet, means for supplying said gaseous medium to the printed side of both traveling web runs on said rollers, suction means for withdrawing said medium after passage along the printed side of said web, and means for varying the cross-section of said channel. 15

THEODOR FUYKERS. 20
